HANDLE FOR LAWNMOWERS OR THE LIKE

Raymond G. Rech, Swansea, Mass., assignor to Arens Controls, Inc., Evanston, Ill., a corporation of Illinois

Filed Oct. 23, 1961, Ser. No. 67,226

Term of patent 14 years

(Cl. D40—1)

Fig. 2.

Fig. 3.

FIG. 1 is a front elevational view of a handle for lawnmowers or the like, embodying my new design;

FIG. 2 is a top plan view thereof; and

FIG. 3 is a side elevational view thereof.

The rear of the handle is essentially the same in appearance as the front, aside from the switch panel.

The dominant features of my design reside in the portions shown in full lines.

I claim:

The ornamental design for a handle for lawnmowers or the like, substantially as shown and described.
